CLAIM

The ornamental design of the truck tool, substantially as
shown and described.

DESCRIPTION

FIG. 1 is a perspective view of the truck tool showing
my new design;

FIG. 2 is a top view thereof;

FIG. 3 is a side view thereof, the opposite side being a
mirror image thereof;

FIG. 4 is a bottom view thereof;

FIG. 5 is an end view of the left end of FIG. 1; and

FIG. 6 is an end view of the right end.
